UNITED STATES PATENT OFFICE

HARRY A. KESSLER, OF CHICAGO, ILLINOIS, ASSIGNOR TO KALMAN STEEL COMPANY, INC., OF CHICAGO, ILLINOIS, A CORPORATION OF DELAWARE

MACHINE FOR THE PRODUCTION OF EXPANDED METAL

Application filed November 2, 1928. Serial No. 316,676.

This invention relates to machines for the production of expanded metal lath and is particularly directed to a machine which is capable of continuously fabricating lath from blanks of determined or undetermined length.

The principal object is to provide a machine which operates with a minimum degree of frictional resistance to the blank and which produces a superior quality of lath quickly and economically.

A further object is to provide a machine applicable to the production of ribbed lath having elongated strands.

15 While the machine preferably consists of various instrumentalities which perform various operations upon the blank, it may be pointed out that the invention primarily resides in the provision of the means by which 20 the blank is widened. Generally stated, the widening means include elements arranged along opposite faces of the blank in rows of diverging or fan-like formation and adapted to engage the blank and move with 25 it a determined distance and in such movement to spread or widen the blank.

An embodiment of the invention is shown in the accompanying drawings, wherein:

Figure 1 is a top plan view of the complete machine.

Figure 2 is a side elevation of the same.

Figure 3 is a view partly in elevation and partly in section showing the expanding rolls and rib-engaging elements.

35 Figure 4 is a perspective of a pair of rib-engaging elements and their connecting link.

Figure 5 is a similar perspective of the opposed rib-engaging elements and connecting link.

40 Figure 6 is a fragmentary section along line 6—6 of Figure 3 showing the engagement of the rib-engaging elements with the driving sprockets.

45 Figure 7 is a section of the widening guides along line 7—7 of Figure 6.

Figure 8 is a similar section of the widening guides taken in advance of the preliminary flattening rolls and near the end of the 50 widening operation.

Figure 9 is a view partly in elevation and partly in section showing the preliminary finishing rolls and the rib-engaging elements.

Figure 10 is a perspective of a fragment of the slotted blank.

Figure 11 is a section through the ribbing rolls during the ribbing operation.

Figure 12 is a top plan view of a fragment of the blank as it appears on emergence from the rib forming rolls.

Figure 13 is a section through the guides between the ribbing and stretching rolls.

Figure 14 is a section through the stretching rolls during the stretching operation.

Figure 15 is a top plan of a fragment of the blank as it appears on emergence from the stretching rolls.

Figure 16 is a section through the widening means prior to the widening operation and showing more particularly the cross section of the blank at that time.

Figure 17 is a section through the blank widening means after the blank has been widened and showing more particularly the cross section of the blank as widened.

Figure 18 is a section through the preliminary finishing rolls.

Figure 19 is a top plan view of a fragment of the blank as it appears upon emergence from the preliminary finishing rolls.

In the manufacture of lath by this machine, a hot or cold blank B may be utilized, a hot blank being preferred. The manufactured lath is preferably ribbed and preferably of the diamond mesh type and, to this end the blank illustrated (see Fig. 10) is characterized by parallel longitudinal slotted and unslotted zones C and D respectively, in which each slotted zone C extends between adjacent unslotted zones D and comprises several longitudinal rows of slits wherein the slits of one row are in staggered or break-joint relation to the slits of adjacent rows in the same zone. The blank B may be slotted by any suitable mechanism (not shown) and having been brought to the desired temperature is ready to be processed by the machine.

As shown and preferred the machine includes the following instrumentalities (see

55

Figs. 1 and 2) which operate upon the slit-
ted blank in the order enumerated, namely,
ribbing rolls R, expanding rolls E, widening
and flattening means W and finishing rolls
F all of which are preferably supported on
a common base or table T.

For the ribbing operation cooperating rolls
R are employed (see Fig. 11). The upper
roll is formed with peripheral channels 10
10 and the lower roll with cooperating peripheral
ribs 11 which operate in the channels 10
and shape the flat non-slitted zones D of the
blank into reenforcing ribs V of suitable
15 cross section such as the inverted V cross
section shown. The ribbing rolls R are also
formed with upper and lower clearances 12
to permit the expansion of, and limit it to,
the marginal portions of each slitted zone C
20 through the lateral pull exerted on the slit-
ted zones during the ribbing operation.

From the ribbing rolls R, the ribbed blank
passes through an intermediate guide G to
the expanding or stretching rolls E. The
guide G, as shown in Figures 1 and 13, prefer-
25 ably employs a series of parallel elements,
each composed of an upper bar 13 which
overlies a rib V and a lower bar 14 arranged
below and conforming to the under side of
the rib, these elements functioning to insure
30 the exact registry of the blank with the ex-
panding rolls E.

The expanding rolls E preferably operate
to stretch the strands of the central portion
35 of all slitted zones, the marginal portions
having been stretched during the ribbing op-
eration (see Fig. 14). The complete stretching
40 of these strands is preferably simultane-
ously accomplished and in a manner such that
each central portion is bent into a series of
parallel longitudinal convolutions, that is to
say so bent as to have a tortuous or sinuous
45 cross section. For this purpose each of the
rolls E is formed with several groups of
peripheral ribs 15 which delimit intermediate
peripheral channels 16, the ribs of one roll
extending into the channels of the other roll
50 and the faces of the channels being spaced
from the cooperating ribs to provide clear-
ances in which the stretching takes place.
55 The outer ribs of each group function to
limit the stretching action to the central por-
tion of each slitted zone and, to this end they
are made of less depth than the intervening
ribs and arranged to engage the blank along
60 the line of demarcation between the central
and marginal portions of each zone, their
depth being such that no displacement of the
marginal portions is effected during the ex-
panding operation.

As the blank emerges from the expanding
65 rolls E, the emerged portions are in a
condition of complete and uniform ex-
pansion and such portions are, therefore, ready
to be deployed, that is to say widened and
thereby returned to a flat cross section. This

operation is performed by the widening and
flattening means W.

The widening operation is accomplished in
a general way by engaging the unslifted por-
70 tions of the blank, in this case the ribs V,
and directing them along diverging paths of
travel so as to increase their mutual separa-
tion progressively as they move away from
the expanding rolls E. As the spacing of
75 the ribs increases, the cross sectional convolu-
tions are gradually reduced and the blank
thus made to approach a flat cross section.
The point at which the flat cross section is
ultimately reached without stretching the
80 strands depends, of course, upon the angle of
divergence and the extent to which the
strands have been elongated. In any case,
when such point is reached, the diverging
movement of the elements is preferably ar-
85 rested so as to prevent any stretching during
this operation.

For the purpose of directing the ribs of
the blank in the manner described, the wid-
ening and flattening means W include a num-
90 ber of opposed elements 17 and 18 arranged
in the path of the ribs of the blank, each pair
of elements being shaped to delimit, between
them, a space of general inverted V outline
95 into which the ribs extend (see Figures 4, 5,
7 and 8). Each pair of elements is adapted
100 to engage a determined portion of a rib and
to move with such portion during the widen-
ing operation, the movement being such that
at some point after the expansion operation,
the mutual lateral spacing between corre-
105 sponding pairs of elements begins to increase
and continues so to do until the cross sec-
tional convolutions connecting the engaged
rib portions are completely returned to a flat
110 cross section. The increase in the spacing
between the corresponding pairs of elements
is accomplished by causing them to move in
diverging paths of travel. In order to make
the widening operation continuous and thus
115 progressively return successive portions of
each rib to a flat cross section, the elements
17 and 18 for each rib are respectively con-
nected in an endless or chain-like series by
links 19 extending between adjacent ele-
120 ments, the arrangement being such as to feed
the elements to the blank at the beginning of
the widening operation and remove them
from the blank at the end of such operation.

The drive of the elements may be effected
in any suitable manner but it is preferably
125 effected by forming the elements 17 and 18
and connecting links 19 with teeth 20 in the
manner of a silent chain and providing, for
driving engagement with the teeth of each
chain of elements, suitably mounted sprock-
ets 21 at the beginning and at the end of the
widening area. While the widening opera-
tion may be started at a point removed from
the expanding rolls E, it is preferably started
130 at the point of emergence of the blank from

- the rolls E. To accomplish this result, the sprockets 21, located at the beginning of the widening area, are made a part of the expanding rolls E (see Figures 3 and 6), each 5 expanding roll having as many sprockets as there are chains of elements. This arrangement not only effects economy in the cost of equipment but has a further advantage in that the elements 17 and 18 when passing 10 between the rolls E, cooperate to engage the ribs and guide them through the rolls. The sprockets 21 located at the end of the widening area are preferably mounted upon rolls 22 (see Fig. 9). These rolls preferably 15 are arranged to perform a preliminary finishing operation and, to this end they are formed with flat surfaces 23 which engage and flatten the expanded portions of the blank.
- 20 The space relation of the elements 17 and 18 during their engagement with the ribs, is maintained by divergently arranged channel guides 24 through which the elements pass, the opposite ends of the guides being tapered 25 to permit a close approach to the expanding rolls E and the rolls 21. The channel guides 24 carry bed strips 25 against which the teeth of the elements ride, these strips being composed of hardened steel to resist wear.
- 30 The marginal edges of the channels also carry wear resisting hardened strips 26 which abut against the sides of the elements to hold them in alignment. The guides 24 are adjustably connected to suitably spaced cross bars 27 by 35 adjusting screws 28, the cross bars being mounted upon the side members of the base or table T. In order to support the weight of the elements 17 during their return movement from the rolls 21 to the expanding roll 40 E, channel guides 29 are provided which are supported on the cross bars 27. The elements 18 are similarly provided with channel guides 30, these being supported on transversely arranged angle bars 31 which are 45 mounted on the side members of the table T.
- In the operation of the machine, the blank passes into the expanding rolls E where the ribs V of the blank are engaged by the elements 17 and 18 and the slotted portion suitably stretched. As the stretched portions of the blank emerge from the rolls, the elements diverge and the blank is thus made to approach a flat cross section which is ultimately reached at the point where the blank enters 50 the preliminary finishing rolls 22. These rolls operate to flatten the strands and then deliver the blank through the guides G' to the final finishing rolls F. The guides G' are of the same arrangement as the guides G previously 55 described. The finishing rolls F operate to engage the entire blank, ribs included, and complete the flattening of the strands as well as giving the product a desired finish.
- 60 The drive of the machine as a whole may be accomplished in any desired manner. As 65

shown the drive is effected from a power shaft 32 which is connected through chains 33 to the various rotating parts, suitable idling gears 34 being utilized to take up the slack in the chains. 70

Having fully described my invention, I claim:

1. In a machine for producing expanded metal from a slotted blank the combination with means for expanding the blank by forming its cross section progressively with displaced components, of means for continuously and progressively widening the blank to a determined extent as it moves away from the expanding means, said widening means including laterally spaced rows of elements in which the elements of each row are adapted to be fed into engagement with successive portions of a blank and to move a determined distance with the engaged portions during which movement the relative spacing of corresponding points in each row is progressively increased so as to increase in like manner the relative spacing of the engaged portions of the blank and thereby widen the blank, and means for so moving the elements. 80

2. In a machine for producing expanded metal from a slotted blank the combination of opposed rolls adapted to engage a blank 85 and form its cross section progressively with displaced components, of means for continuously and progressively widening the blank to a determined extent as it moves away from the expanding rolls, said widening means including opposed sets of blank engaging elements, each set having a plurality of laterally spaced endless chain-like rows of elements in which each row is adapted for endless movement over a fixed path, a portion 100 of which extends from the expanding rolls forwardly to a determined extent and in diverging relation with corresponding portions of the paths of other rows in the same set, the elements of one set being in 105 opposed relation with the corresponding elements of the opposed set during the diverging movement, the rows of elements in one set having driving engagement with one of the expanding rolls, the opposed set of elements having driving engagement with the opposed expanding roll, opposed series of sprockets arranged at the end of the diverging area in driving engagement respectively with the opposed sets of elements, and means for 110 driving the assembly, the opposed elements being adapted to engage between them determined portions of a blank which is fed between the expanding rolls and to move with such portions throughout the diverging 115 movement so as to increase the mutual spacing of corresponding engaged portions of the blank as they move away from the expanding rolls and thereby widen the blank. 120

3. In apparatus for producing expanded 130

metal from a slitted blank, the combination of means for displacing from the plane of the blank a series of unit panels, each consisting of a series of rows of strands, and incident to such displacement stretching the strands in said panels, means for straightening the blank in cross section comprising laterally spaced rows of elements in which the elements of each row are adapted to be fed into engagement with successive portions of the blank adjacent the said panels during which movement the relative spacing of corresponding points in each row is progressively increased so as to increase in like manner the relative spacing of the engaged portions of the blank and thereby widen the latter and means for so moving the elements.

4. In apparatus for producing expanded metal from a blank having longitudinal slit-
20 zones connected by longitudinal unslotted zones, the combination of means for displacing from the plane of the blank a series of unit panels, each consisting of a series of rows of strands, and incident to such displacement stretching the strands in said panels, means for straightening the blank in cross section comprising laterally spaced rows of elements in which the elements of each row are adapted to be fed into engagement with successive portions of a longitudinal unslotted zone and to move a determined distance with the engaged portion, during which movement the relative spacing of corresponding points in each row of elements is progressively increased so as to increase in like manner the relative spacing of the engaged portions of the blank thereby widening the latter and means for so moving the elements.

40 5. In apparatus for producing expanded metal from a blank having longitudinal ribbed zones connected by longitudinal slit-
25 zones, the combination of means for displacing from the plane of the blank a series of unit panels, each consisting of a series of rows of strands, and incident to such displacement stretching the strands in said panels, means for straightening the blank in cross section comprising laterally spaced rows of elements in which the elements of each row are adapted to be fed into engagement with successive portions of a longitudinal ribbed zone and to move a determined distance with the engaged portions during which movement the relative spacing of corresponding points in each row is progressively increased so as to increase in like manner the relative spacing of the engaged portions of the blank thereby widening the blank and means for so moving the elements.

60 6. In apparatus for producing expanded metal from a slitted blank, the combination of means for displacing from the plane of the blank a series of unit panels, each consisting of a series of rows of strands and incident to

such displacement stretching the strands in said panels, means for straightening the blank in cross section comprising opposed sets of blank engaging elements, each set being composed of at least two laterally spaced endless rows of elements, the rows of one set corresponding in arrangement to the rows of the other set and the elements of corresponding rows being adapted for movement along circuitous paths which bring such elements successively into opposed relation for a determined distance of travel during which travel they co-operate to engage a determined portion of the blank between them and to maintain their engagement with such portion, their movement being in a direction such as to increase progressively to a determined extent the mutual spacing of the rows of both sets, whereby the mutual spacing of corresponding engaged portions of the blank is increased in like manner and the blank thereby widened and means for so moving the elements.

7. In apparatus for producing expanded metal from a slitted blank, the combination of means for displacing from the plane of the blank a series of unit panels, each consisting of a series of rows of strands, and incident to such displacement stretching the strands in said panels, means for straightening the blank in cross section comprising a plurality of laterally spaced chain-like rows of elements in which the elements of each row are respectively adapted for movement in a fixed circuitous path during a determined portion of which the mutual spacing between corresponding elements of the various rows increases, the corresponding elements being adapted to engage corresponding portions of the blank as they approach the point at which their mutual spacing begins to increase and to maintain their respective engagement with their respective portions while their spacing increases, whereby the mutual spacing of the corresponding engaged portions of the blank is increased in like manner and the blank widened and means for moving the elements.

8. In apparatus for producing expanded metal from a slitted blank, the combination of means for displacing from the plane of the blank a series of unit panels, each consisting of a series of rows of strands and incident to such displacement stretching the strands in said panels, means for straightening the blank in cross section comprising a plurality of laterally spaced chain-like rows of elements in which the elements of each row are respectively adapted for movement over a fixed circuitous path during a determined portion of which the mutual spacing between the corresponding elements of the various rows increases, the corresponding elements being adapted to engage corresponding portions of the blank as they approach the point at which their mutual spacing be-

gins to increase and to maintain their respective engagement with their respective portions while their spacing increases, whereby the mutual spacing of the corresponding engaged portions of the blank is increased in like manner and the blank widened, a series of sprockets arranged to guide the elements of each row into engagement with the blank at the beginning of the widening operation, another series of sprockets arranged to guide the elements out of engagement with the blank after it has been widened and means for driving the elements.

9. In apparatus for producing expanded metal from a slitted blank, the combination of means for displacing from the plane of the blank a series of unit panels, each consisting of a series of rows of strands, and incident to such displacement stretching the strands in said panels, means for straightening the blank in cross section comprising opposed sets of blank engaging elements, each set including a plurality of laterally spaced endless rows of elements in which each row is adapted for movement over a fixed path, a portion of which is in diverging relation with corresponding portions of the paths of the other rows in the same set, the elements of one set being in opposed relation with corresponding elements of the opposed set during the diverging movement, and means for driving the elements, the opposed elements being adapted to engage between them determined portions of the blank which is fed between the sets and to move with such portions throughout the diverging movement so as to increase the mutual spacing of corresponding engaged portions of the blank and thereby widen the same.

10. In apparatus for producing expanded metal from a slitted blank, the combination of means for displacing from the plane of the blank a series of unit panels, each consisting of a series of rows of strands and incident to such displacement stretching the strands in said panels, means for straightening the blank in cross section, comprising opposed sets of blank engaging elements, each set including a plurality of laterally spaced endless chain-like rows of elements in which each row is adapted for movement over a fixed path, a portion of which is in diverging relation with corresponding portions of the paths of the other rows in the same set, the elements of one set being in opposed relation with corresponding elements of the opposed set during the diverging movement, a pair of rolls respectively arranged in each set at the beginning and at the end of the diverging area, said rolls having driving engagement with the elements, and means for driving the rolls, the opposed elements being adapted to engage between them determined portions of the blank which is fed between the set and to move with such portions throughout the

diverging movement so as to increase the mutual spacing of corresponding engaged portions of the blank and thereby widen the same.

11. In apparatus for producing expanded metal from a slitted blank, the combination of means for displacing from the plane of the blank a series of unit panels, each consisting of a series of rows of strands, and incident to such displacement stretching the strands in said panels, means for straightening the blank in cross section comprising opposed sets of guides, each set including a plurality of laterally spaced channel members arranged in diverging relation, the members of one set being in opposed relation to similar members of the opposed set, a series of sprockets arranged at the beginning and end of each set of channel members, each series being laterally spaced to correspond with the spacing of the adjacent end of the channel members, an endless row of chain-like elements for each channel member, each row extending through the channel of their respective member and having driving engagement with the sprocket at each end of such member, the elements in a channel member of one set being in opposed relation to the elements in the corresponding channel member of the opposed set, and means for driving each series of sprockets so as to move the elements of each row successively into and through the channel of their respective member and in a direction such that the spacing of corresponding points in the rows of each set is progressively increased as they move through the channels, the opposed elements being adapted to engage between them determined portions of the blank which is fed between the sets and to move with such portions throughout the diverging movement so as to increase the mutual spacing of corresponding engaged portions of the blank and thereby widen the same.

12. In apparatus for producing expanded metal from a slitted blank, the combination of means for displacing from the plane of the blank a series of unit panels, each consisting of a series of rows of strands, and incident to such displacement stretching the strands in said panels, means for straightening the blank in cross section comprising opposed sets of blank-engaging elements, each set including a plurality of laterally spaced endless chain-like rows of elements in which each row is adapted for movement over a fixed path, a portion of which is in diverging relation with corresponding portions of the paths of the other rows in the same set, the elements of one set being in opposed relation with corresponding elements of the opposed set during the diverging movement, a pair of rolls respectively arranged in each set at the beginning and at the end of the diverging area, said rolls having driving engagement with the elements, and means for driving the rolls, the opposed elements being adapted to engage between them determined portions of the blank which is fed between the set and to move with such portions throughout the

ment with the elements, and means for driving the rolls, the opposed elements being adapted to engage between them determined portions of the blank which is fed between the sets and to move with such portions throughout the diverging movement so as to increase the mutual spacing of corresponding engaged portions of the blank and thereby widen the same, and the rolls at the end of the widening area being adapted to engage and flatten portions of the blank extending between the portions engaged by the blank-engaging elements.

In testimony whereof I hereby affix my signature.

HARRY A. KESSLER.
